(57) **CLAIM**

The ornamental design for a ball, as shown and described.

DESCRIPTION

FIG. 1 is a front perspective view of a ball showing the claimed design;

FIG. 2 is a rear perspective view thereof;

FIG. 3 is a left side perspective view thereof;

FIG. 4 is a right side perspective view thereof;

FIG. 5 is a top perspective view thereof;

FIG. 6 is a bottom perspective view thereof; and,

FIG. 7 is a perspective view thereof.

The portioning of the ball panels in FIGS. 1-6 is subject to optical distortion. FIG. 7 shows the proportional sizing of the square pattern elements.

1 Claim, 7 Drawing Sheets(56)
